UNITED STATES PATENT OFFICE.

HAROLD G. WARR, OF CHICAGO, ILLINOIS, ASSIGNOR TO THE P. & M. CO., OF CHICAGO, ILLINOIS, A CORPORATION OF ILLINOIS.

ANTICREEPER WITH PIN-LOCK.

1,160,116.

Specification of Letters Patent.

Patented Nov. 9, 1915.

Application filed August 11, 1914. Serial No. 856,271.

To all whom it may concern:

Be it known that I, HAROLD G. WARR, a citizen of the United States, residing at Chicago, in the county of Cook and State of Illinois, have invented new and useful Improvements in Anticreepers with Pin-Locks, of which the following is a full, clear, concise, and exact description, reference being had to the accompanying drawing, forming 10 a part of this specification.

My invention relates to improvements in anti-creepers and more particularly to locking means for maintaining the parts in their most effective position for gripping the rail 15 base.

For the purpose of disclosing the features of the invention, I have illustrated the locking means in conjunction with a two piece anti-creeper, parts of which have wedging 20 engagement with each other beneath the rail base.

The object of the invention is to provide improved locking means for a rail anchor of this general type, and more particularly, 25 means which cannot work loose or be accidentally withdrawn.

Figure 1 of the drawings is a top plan view of a rail anchor, which embodies one form of the invention. Fig. 2 is an elevation 30 thereof, partly in section. Fig. 3 is a section on the line 3—3 of Fig. 2. Fig. 4 is a bottom view of part of the anchor. Fig. 5 is a partial sectional elevation of a modified structure. Fig. 6 is a similar view of a further 35 modification.

The rail anchor comprises two parts, the larger of which, 1, may be called the clip, and the smaller of which, 2, may be called the mate. The clip and the mate are each 40 provided with suitably reinforced jaws 3, 3 of customary configuration, which are adapted to firmly grip the rail base. The clip is provided with a recess or groove in its upper face, one wall of which is formed by an upwardly inclined rib 4, the mate being provided with a downwardly inclined rib 5, the inner faces of said ribs engaging each other to lock the parts against separation. The 45 meeting faces or walls are inclined somewhat 50 from a vertical plane to interlock the parts firmly against vertical separation, and are also arranged somewhat diagonally with respect to the longitudinal axis of the rail, whereby as the mate is driven forward, the 55 jaws 3—3 approach each other and grip the

rail base 6 firmly. The forward movement of the clip 1 is resisted by the usual cross-tie 7 against which the downwardly extending bearing face 8 abuts in the usual manner.

The inclined wall 5 of the mate is not of the same vertical height throughout its length, but decreases in height from front to rear as shown in Fig. 3, thus providing a wedging surface 9 which slopes upwardly 60 with respect to the base of the rail. In order to hold the mate against any rearward movement after it has been driven forward as far as possible, a locking pin 10 is driven through a pair of aligned openings 11, 12, 70 in the clip, said pin being thrust against the wedging surface 9, thereby forming a positive lock. The pin, which may be made of malleable iron or other material adapted to bend without breaking, is driven into the 75 hole as far as it will go after the clip and the mate have been driven onto the rail to their most effective gripping position. The pin is circular in cross section except that it is gradually cut away from near one end to 80 the other, giving it a considerable taper and providing a flat upper surface. The circular portion conforms to the walls of the openings 11, 12 (see Fig. 3), the lower parts 85 of which are connected so that the pin has a bearing area of considerable length beneath the point where it engages the wedging surface 9 (see Fig. 2). A deflecting wall or abutment 13 is provided in the path of said pin causing it to be deflected downwardly as 90 it is being driven into position, as shown in Fig. 2. The wall of said deflector which is first engaged by said pin, is so disposed as to impart a slight twisting tendency thereto as 95 the flat upper surface of the pin rides over said deflector. This twisting is aided by the fact that said pin is not driven in a direction exactly at right angles to the axis of the rail and hence to the edge of the deflector which is parallel thereto, but is driven in 100 at a slight angle as shown in Figs. 1 and 4. The action of the pin is not only to lock the parts against loosening, but it even results in tending to cause a further tightening thereof due to the fact that it tends to draw 105 the clip downwardly away from the mate which separation is resisted by the under cut walls 5 and 6. These walls which are doubly inclined have, therefore, a double wedging 110 effect, viz., when the parts on which they

are formed move in a proper direction either horizontally or vertically. The twisting of the pin further increases the security of the engagement as the flat upper surface thereof is crowded more firmly against the wedging surface 9. The pin being bent is prevented from working loose or being accidentally withdrawn although it may be withdrawn if occasion demands by using sufficient force; 10 for example, a claw-bar may be applied to the head of the pin at the side of the rail anchor and the pin withdrawn during which withdrawal it is automatically straightened to a greater or less extent.

15 In the modification shown in Fig. 5, the openings 14, 15 through which the pin is driven are not in exact alinement, one being horizontal and the other inclined downwardly as shown. The pin is, therefore, deflected downwardly by engaging the upper inclined wall of the second opening, through which it passes.

In Fig. 6, a further modification is shown wherein substantially alined openings 16 and 17 are provided into which the pin is driven. Between said openings, a recess or depression 18 is provided into which the pin is forced to a slight extent by the lower surface 9 of the rib 5 as it is being driven home. 30 This produces a slight offset or kink in the pin, thereby preventing ready removal thereof.

It will be seen that this lock prevents a relative movement of the clip and mate in such a direction as to cause a loosening of their grip on the rail base. However, no obstruction is offered to a relative movement in such a direction as to increase such gripping action. Accordingly, if the thrust 40 of the rail should cause a slight forward movement of the mate, the result will be an increased gripping of the rail base by the jaws, the locking pin interfering in no wise with this action. Said pin may perhaps be driven in a little farther after such a readjustment, in order to better lock the parts in their final position, any permissible movement, either of the mate or of the pin, however, being in such a direction as to insure 45 greater security rather than diminish security. It will thus be seen that the mate may be locked in any position of adjustment which it may assume.

As previously stated, the invention is not limited to the details of the present disclosure except where limitations appear in the appended claims, as various other forms may be devised which fall within the scope of said invention.

60 Having thus described my invention what I claim as new and desire to secure by Letters Patent of the United States is:

1. A rail anchor comprising a plurality of members relatively movable in a direction 65 which is substantially parallel to the length

of the rail, two of said members having jaws which grip the rail base, certain of said members having engaging surfaces which are arranged somewhat diagonally with respect to the length of the rail to 70 cause said jaws to grip the rail base upon relative movement of said parts, one of said surfaces terminating in a face which is non-parallel with respect to the longitudinal axis of the rail and means bearing against 75 said face for wedging said parts against movement in such direction as would relax said grip.

2. A rail anchor comprising two parts, each having a jaw for gripping the rail base, 80 said jaws having walls interlocked beneath the rail base, one of said walls decreasing in height from front to rear and a pin arranged transversely with respect to said walls and engaging said tapering wall. 85

3. A rail anchor comprising a clip and a mate, said clip having a diagonally arranged channel in the upper face thereof, the walls on the opposite sides of said channel being provided with substantially alined 90 openings in advance of the rear of said mate.

4. In a rail anchor, a pair of relatively movable parts one of which has an inclined surface thereon, a pin seated in the other of 95 said parts and arranged to bear against said inclined surface and means causing a twisting of said pin as it is driven into position to increase the security of the engagement.

5. In a rail anchor, a pair of relatively 100 movable parts, one of said parts having a recess, the side walls of which have openings therein, the other of said parts terminating in an inclined surface adjacent to said openings, a pin passing through said openings 105 and engaging said inclined surface to lock said parts and means for automatically deflecting said pin as it is being driven into position to prevent withdrawal thereof.

6. A rail anchor comprising two parts, 110 each having a rail gripping jaw, one of said parts having a diagonally arranged slot, the base of which is substantially horizontal, the other of said parts having a downwardly extending rib received within said slot, the 115 lower wall of said rib being inclined upwardly from the front to the rear and a pin passing transversely through said slot and engaging said sloping wall to lock the part against rearward movement. 120

7. A rail anchor comprising a clip and a mate, said mate having a jaw and having a downwardly extending rib, the under surface of said rib tapering upwardly from one end to the other.

8. In a rail anchor, two parts, each having a jaw to grip one side of the rail base, said parts having under cut walls engaging each other beneath the base of the rail, openings through one of said parts, a pin passing 130

through said openings and engaging the edge of one of said walls, said pin being arranged diagonally with respect to the axis of the rail and a deflector engaged by said pin arranged with its edge substantially parallel to said axis.

In witness whereof, I have hereunto sub-

scribed my name in the presence of two witnesses.

HAROLD G. WARR.
